PORABLE HEATER

Vernon C. Hines and Albert B. Callahan, Jr.,
Denver, Colo., assignors to The International
Manufacturing Co., Denver, Colo., a corpora-
tion of Nevada

Application October 29, 1952, Serial No. 22,038

Term of patent 14 years

(Cl. D81—10)

To all whom it may concern:

Be it known that we, Vernon C. Hines and Albert B. Callahan, Jr., both citizens of the United States, residing at Denver, in the county of Denver and State of Colorado, respectively, have invented a new, original, and ornamental Design for a Portable Heater, of which the following is a specification, reference being had to the accompanying drawing forming a part thereof.

Figure 1 is a perspective view showing the front and one side of a portable heater, showing our new design; and

Fig. 2 is a perspective view showing the rear end and the opposite side of the portable heater.

We claim:

The ornamental design for a portable heater, as shown.
